LOOM SHUTTLE

Dana L. Wiggin, Southbridge, Mass., assignor to
Albert E. Leon, Belmont, Mass.Application November 27, 1933, Serial No. 699,829
Renewed August 11, 1936

5 Claims. (Cl. 139—207)

This invention relates to loom shuttles and particularly that type of shuttles provided with bobbin forks adapted for use in weft replenishing looms that are provided with means for driving a full bobbin into the shuttle when the filling on the bobbin, previously contained in the shuttle, has become exhausted.

As is well known, the hammer, which at the same operation drives out the old bobbin and drives in the new bobbin, produces a very powerful blow or shock upon the bobbin holding fork when changing bobbins and consequently subjects the fork and its attaching means to repeated and heavy strains tending to loosen the fork in its bobbin. From time to time various means have been proposed and practiced for meeting these exacting conditions but without complete success.

According to common practice, the fork structure embraces a fork proper comprising a rearward U-shaped shank portion with forwardly extending, more widely spaced bobbin-engaging and holding jaws. A spreader or spacing block was forced between the side members of the shank and a deflector or guide plate was formed with rearward top and bottom extensions adapted to tightly grip the upper and lower edges of the fork shank; these three parts forming an assembled unit or fork structure which were inserted in the channelled rear portion of the shuttle body and were then attached in place by the usual horizontal tie bolt passing through aligned perforations in the shuttle body, the fork shank and the spreader block. Since the impact of the bobbin being inserted was exerted in a downward direction upon the forward end portions of the bobbin fork, it is clear that the horizontal tie bolt could have no effect in resisting the downward torque which such impact tended to produce on the fork. This torque was commonly resisted principally by the bottom shelf or thin web of wood forming the floor of the fork-receiving recess, which shelf was necessarily quite thin since it was necessary to cut away the shuttle body nearly to the bottom of the shuttle in order to make room for properly receiving the fork structure. To relieve the strains on the bottom shelf it was proposed to use a wood screw tapped into the wood after passing through a rearward extension of the top member of the guide plate, which was very unsatisfactory because the repeated stresses on the wood screw tended to work it loose and render it valueless. Next it was proposed to use a vertical through bolt passed down through the fork shank to the

rear of the spreader block. This, however, had little effect in relieving strains on the thin bottom shelf, since such through bolt became to all intents and purposes a part of the fork structure assemblage and had no engagement with the solid wood of the shuttle.

The principle of construction embodied in the present invention avoids the objectionable weakness that was inherent in bobbin fork attaching means by providing a body of superior strength through avoidance of excessive cutting away of the wood of the rear part to receive the fork structure and at the same time providing an attaching construction by which a vertical through bolt is inserted in and held by the solid wood body of the shuttle throughout almost its entire length, while forming clamping engagement with the rear end portions of the guide plate upon the interposed solid wood of the shuttle at a substantial distance to the rear end of the fork shank sufficient to allow the overlapping end portions of the plate to be sprung toward each other into powerful gripping engagement with the solid portion of the shuttle body. This and other features of the invention will be particularly described in the accompanying specification and will be defined in the claims hereto annexed.

In the accompanying drawing there is illustrated a simple and convenient construction illustrating and embodying the principles of this invention, in which:

Fig. 1 is a plan view of the rear half of a shuttle body containing the improved bobbin fork construction.

Fig. 2 is a central vertical section on plane 2—2 of Fig. 1.

Fig. 3 is a horizontal section on the plane 3—3 of Fig. 2.

The shuttle body or blank of which the shuttle is made is of the usual construction comprising the rear part 1 and a similar forepart, not shown, integrally connected by side walls 2 forming the usual bobbin chamber of the shuttle. The forward end of the rear part is cut away down to the bottom shelf 4, the form of the recess or fork-receiving well being approximately semicircular in contour, as shown at 3. Extending rearwardly from the bobbin-receiving well is a narrow channel or recess 5 dimensioned to snugly receive and fit around the middle U-shaped shank portion 6 of the shuttle fork, whose arms are extended and spread apart forwardly to form the bobbin holding jaws 7 in the usual manner, except that the shank portion and its receiving recess 5 is substantially shorter in the axial di-

rection of the shuttle than has heretofore been the practice.

The deflector or guide plate 8 comprises the inclined forward portion for directing the base 5 of the bobbin toward the jaws and an upper arm or extension 9 and a lower arm or extension 10, which extend rearwardly a considerable distance beyond the rear end of the fork when the deflector plate is forced over the shank portion of 10 the fork in order to provide clamping tongues or extensions 9^a and 10^a which are inserted in horizontal receiving slots or slits formed in the walls 5 of the shank-receiving channel. The usual spreader or spacing block 11 is forced between the 15 sides of the shank member 6 and abuts against the bent rear end of the shank. A tie bolt 12 passes horizontally through the rear part of the shuttle and aligned holes in the shank and in the spreader 11 and serves to firmly anchor the 20 fork structure against displacement axially of the shuttle.

To provide an anchorage that will resist the downward thrust upon the clamping jaws of the fork, there is provided a vertical anchoring bolt 25 14 which passes through aligned openings in the rearward extensions 9^a and 10^a of the guide plate and which, in conjunction with the clamping nut 15, serves to powerfully clamp the two extensions firmly upon the interposed solid wood portion 1^a 30 of the body. This vertical through bolt is located at a substantial distance behind the rear end of the fork shank so that the ends 9^a, 10^a may be sprung into tight clamping engagement by the bolt and nut with the interposed wood, since obviously such clamping action on the wood could 35 not be exerted by a vertical through bolt when passed down inside of the shank portion. It will be seen that the anchoring through bolt has firm engagement with the solid wood of the shuttle 40 throughout almost its entire length, while at the same time producing simultaneously a strong clamping action upon the shank of the fork as well as upon the solid wood body of the shuttle, so that a permanent and reliable and direct 45 anchorage of the fork structure to the solid part of the shuttle body is always maintained. The very compression of the extensions 9^a and 10^a upon the interposed wood by the powerful clamping action of the bolt and nut serves to lock the 50 through bolt against loosening, since it has much of the effect of a spring lock-nut washer. With this construction the through bolt has such a large and firm anchorage in the wood body itself, that it opposes a powerful resistance to any 55 downward torque of the fork structure. Moreover, the mode of recessing or cutting the rear part avoids the excessive cutting away of the material and the consequent weakening of the rear part or heel of the shuttle body. With this 60 principle of construction there is provided a strong substantially unweakened shuttle body and a strong attaching means for firmly and securely anchoring the fork structure to that body, both bolts being firmly held in the solid wood of the 65 shuttle body in perpendicular relation to each other.

What I claim is:

1. A loom shuttle embracing in its construction a bobbin fork structure comprising a bobbin fork having bobbin-holding jaws and a rearward U-

shaped shank with an interposed spreader, and a deflector element having an inclined middle portion with rearward top and bottom extensions gripping upon the top and bottom faces of the fork shank and projecting a substantial distance 5 rearwardly of the end of the shank to embrace a solid portion of the shuttle body, a vertical anchoring bolt passing through aligned openings in said top and bottom projections and the interposed solid wood of the shuttle, and a clamping 10 nut attached to the end of said bolt, thereby positively clamping the fork structure directly to the shuttle body rearwardly of said shank.

2. The combination with a bobbin fork comprising gripping jaws and a rearward shank member, 15 of a deflector element having top and bottom rearwardly extending fork clamping members whose rear ends project a substantial distance back of the fork shank to embrace an intervening body portion of the shuttle body, and 20 an anchoring bolt extending vertically through the projecting rear ends of the plate and the interposed intervening portion of the shuttle body, and acting to clamp both clamping members upon the compressible solid wood to the rear of the 25 bobbin fork.

3. The combination with a shuttle body of a bobbin fork comprising a rear shank portion and forwardly extending bobbin gripping jaws, a guide element having top and bottom rearward fork-embracing extensions, a vertical through bolt inserted in, and engaged by, the solid shuttle body for the greater part of the bolt length outside and behind the rear end of the fork, said bolt penetrating through the rear end portions of the extensions of the guide element, thereby clamping said extensions firmly upon both the intervening fork shank and the intervening solid portion of the shuttle body.

4. In a loom shuttle, the combination with a 40 shuttle body recessed for the reception of a bobbin fork structure, of a fork comprising a pair of bobbin holding jaws and a rearwardly extending shank member, a deflector plate provided with rearwardly extending top and bottom shank 45 clamping members having their rear end portions projecting substantially back of the end of the shank and provided with vertically aligned perforations, and anchoring means penetrating said 50 perforated end portions for clamping them upon an intervening portion of the shuttle body.

5. The combination with a shuttle body recessed for the reception of a bobbin fork structure, of a bobbin fork comprising gripping jaws and a rearwardly extending shank member, a 55 fork holding guide element having top and bottom rearward extensions embracing the top and bottom faces of the fork shank and having perforated end portions projecting rearwardly beyond the shank and embracing between them a solid portion of the shuttle body, said top and bottom extensions being fitted into undercut horizontal slots formed in the side walls of the shank-receiving recess, and a vertical bolt penetrating the projecting perforated rear end portions of the guide element and forming positive 60 interlocking anchoring connection between the body and said guide member.
